C. I. HALL

CURRENT LIMITER

Filed Jan. 25. 1921

Fig. 2.

Inventor:
Chester I. Hall,
by *Albert F. Davis*
His Attorney.

UNITED STATES PATENT OFFICE.

CHESTER I. HALL, OF FORT WAYNE, INDIANA, ASSIGNOR TO GENERAL ELECTRIC COMPANY, A CORPORATION OF NEW YORK.

CURRENT LIMITER.

Application filed January 25, 1921. Serial No. 439,867.

To all whom it may concern:

Be it known that I, CHESTER I. HALL, a citizen of the United States, residing at Fort Wayne, in the county of Allen, State 5 of Indiana, have invented certain new and useful Improvements in Current Limiters, of which the following is a specification.

This invention relates to current limiters, and more particularly to such limiters arranged to interrupt the supply to a load at short intervals when it reaches a definite maximum value.

Such devices have usually been built in the form of an electromagnet and an armature, the coil of the electromagnet being placed in series with the load and the armature serving to break the contact when it is attracted by the electromagnet. This causes the deenergization of the magnet and 20 a corresponding resumption of the load. If the load still exceeds the permissible value, the armature is again attracted and the load interrupted. This intermittent flickering continues until the load is reduced to the 25 proper value. Such devices on the whole have certain disadvantages. For example, the length of time for which the contacts are opened may be so short that such loads as heating devices may still be operated efficiently, although the current is on intermittently. It is one of the objects of my invention to render the time interval during 30 which the contacts are open appreciably long so that no form of load whatever may be satisfactorily operated while this successive interruption of the circuit is taking place, and the customer in order to get satisfactory service is forced to reduce his load to the value agreed upon beforehand as 35 the maximum permissible. Another object of my invention is to construct a device in such a way that an accurate adjustment may be made of the value of the load at which the contacts will begin to open and close 40 intermittently. Other objects and advantages will become apparent as the description proceeds.

For a better understanding of my invention reference is to be had to the following 45 specification together with the accompanying drawings, in which Fig. 1 is a front view of the electromagnetic current limiter built according to my invention and a schematic wiring diagram showing its mode of

connection to the circuit; and Fig. 2 is a 55 side view of the device.

Referring now more in detail to the drawings, in which like reference characters refer to like parts throughout, at 11 is designated an appropriate base or support for all of 60 the parts of the device. This may be conveniently made of some kind of insulating material. The electromagnet 12 is provided with a core 13 shown in this instance as 65 made up of laminations so that the device 70 may be used either on an alternating current circuit or on a direct current circuit. Cooperating with the core 13 is a pivoted armature 14 having a stop 15, preferably 75 of soft yielding material such as felt so as to reduce the noise during operation. The stop 15 acts against the end 16 of the armature 14 which is shown as appropriately weighted so as to keep it away from the 80 pole face 17 of the core 13. Metallic conducting pieces 18 and 19 are provided and securely fastened to the base 11, which 85 conducting pieces serve to accommodate binding posts 20 and 21, as well as stop 15. The wires 22 and 23 connect these posts to the 90 load and the source as indicated in Fig. 1. The circuit through the limiter and load may be traced as follows: wire 23, binding post 21 and 24, electromagnet 12, a binding 95 post 25 and from there to a pivoted lever or support 26 which carries a movable contact piece 27 and is appropriately weighted, as for example, by the weight 40. The movable contact piece 27 coacts with the 100 stationary contact piece 28 carried by the metallic member 18 to which the binding post 20 is connected. From binding post 20 the wire 22 leads to the load and the source. It is thus evident that the electromagnet 12 is in series with the load and 105 has its circuit completed through the movable contact 27 and stationary contact 28.

The pivoted support 26 is carried by a plate 29 securely fastened to the base 11. Furthermore, this support is so formed as 110 shown in Fig. 2 that it extends directly above the pivoted armature 14 so that when said armature 14 is attracted to the pole on face 17 upon energization of the electromagnet 12, it strikes against said lever 26, 115 rotating it in counterclockwise direction as viewed in Fig. 2, and opening the contacts 27 and 28. The armature must travel an

appreciable distance before it strikes the lever 26, so that the contacts are opened at a high velocity. The moment of inertia of weight 40 is sufficiently great to cause the 5 pivoted lever 26 to keep on traveling even after the armature 14 has reached the end of its travel toward pole face 17. The movement of the support 26 continues until it strikes the stop 30, in this instance, formed 10 integral with plate 29. By the time the lever 26 returns to the normal position shown in Fig. 2 an appreciable interval of time has elapsed so that a heating device, for example, could not be efficiently operated. The pivoted lever 26 and the stop 30 are so arranged that there is no danger 15 of this lever staying in the open position, since the force of gravity always tends to close the contacts.

20 Under some circumstances it may be advisable to reduce the load to an inappreciable constant value in case a very large load is attempted to be taken. For example, if as much as three or four times the limiting load 25 is reached, it may be advisable to shunt the contact pieces 27 and 28 by a comparatively large resistance 31 so that upon opening of the contacts there is still a path for the current through this resistance, and if the load 30 is sufficiently great this current is large enough to attract armature 14 and hold it in its attracted position. Under such circumstances, a small steady load is obtained, until the number or kind of translating devices making up the load is changed nearer 35 to normal. When this happens the armature 14 is released and the resistance 31 short-circuited.

One of the main features of my invention 40 resides in the particular way in which the core 13 for the electromagnet 12 is supported, so that accurate adjustment of the air gap between the armature 14 and the pole face 17 may be obtained. For this purpose I pivot 45 the armature 14 upon the core member 13 by means of the pivot pin 32. Adjacent to this pivot pin 32 I provide a pivotal support 33 for the entire core 13. This pivotal support fastens to the base 11 as may be 50 ascertained by an inspection of Fig. 2. The other end of the core 13 carries a member provided with a slot 34 through which passes appropriate fastening means such as a screw 55, so as to hold the core in its adjusted position about the pivotal support 33. It is evi-

dent that by loosening the screw 35 and turning the entire core about 33 as a pivot, which pivot has an axis perpendicular to the plane of movement of the armature 14, the pole face 17 may be brought nearer to or 60 further from the armature 14. After the proper adjustment is made the fastening means 35 may again be tightened. Thus an extremely accurate adjustment of the air gap 65 between the armature and core is obtained. The screw 35 is in this instance shown as threaded into a member 36 rigidly fastened to the base 11. Furthermore, the slot 34 is 70 appropriately carried by the bottom plate 37 of the core between which plate and the top plate 38 the laminations of the core are compressed. For compressing these laminations the pivotal support 33 may be used, as well as another fastening means such as the screw 39. 75

While I have shown in the accompanying drawings but one embodiment of my invention, I do not wish to be limited thereto but aim to embrace in the appended claims all modifications falling fairly within the scope 80 of my invention.

What I claim as new and desire to secure by Letters Patent of the United States, is:—

1. In a current limiter having contacts, an electromagnet, a core for said electromagnet, 85 an armature for operating the contacts, a pivotal support for said core, a pivot carried by said core for the armature adjacent the pivotal support for the core, said parts being so arranged that the adjustment of the core 90 about its pivot changes the deenergized position of the armature with respect to the core, and means for adjusting the angular position of said core about its pivotal support.

2. In a current limiter having contacts, an electromagnet, a core for said electromagnet, 95 an armature for operating the contacts, a pivot for said armature carried by said core, a base for independently supporting the contacts and electromagnet, a pivotal support 100 extending from the base through the core adjacent the pivot for the armature, said core having a slot, and fastening means passing through said slot, whereby said core 105 may be angularly adjusted about its pivotal support.

In witness whereof, I have hereunto set my hand this 24th day of January, 1921.

CHESTER I. HALL.
